United States Patent Office

Des. 212,355
Patented Oct. 8, 1968

212,355

VEHICLE FOR TRANSPORTING CRANES

Nolan K. Rhoades, Beloit, Wis., assignor to Bucyrus-Erie Company, Milwaukee, Wis., a corporation of Delaware

Filed Sept. 13, 1967, Ser. No. 8,590

Term of patent 14 years

(Cl. D14—3)

Fig. 3

Fig. 4

Fig. 5

Fig. 6

FIG. 1 is a side view of a vehicle for transporting cranes embodying the invention,

FIG. 2 is a plan view of the vehicle shown in FIG. 1,

FIG. 3 is a front view of the vehicle shown in FIG. 1,
FIG. 4 is a view in section of the vehicle shown in FIG.

1 taken on the plane 4-4,

FIG. 5 is a view in perspective of the vehicle in FIG. 1,
and

FIG. 6 is a view in perspective of a second embodiment
of the invention in which a second cab similar to the first
cab is included in the design, the left side and rear of the
second cab being a mirror image of the right side and
rear of the first cab.

The dominant features of the design reside in the portions shown in full lines.

I claim:

The ornamental design for a vehicle for transporting
cranes, substantially as shown and described.
